UNITED STATES PATENT OFFICE

156,013

DESIGN FOR A FISHING LURE RETRIEVER

John S. Knaur, Denison, Tex.

Application December 10, 1948, Serial No. 150,088

Term of patent 7 years

(Cl. D31—4)

To all whom it may concern:

Be it known that I, John S. Knaur, a citizen of the United States of America, residing at Denison, in the county of Grayson and State of Texas, have invented a new, original, and ornamental Design for a Fishing Lure Retriever, of which the following is a specification, reference being had to the accompanying drawing, forming a part thereof.

Fig. 1 is a side elevational view of a fishing lure retriever, showing my new design,

Fig. 2 is a side elevational view of the retriever, shown in its extended position with its handle end broken away,

Fig. 3 is a side elevational view of the upper end of the retriever,

Fig. 4 is a top end view of the retriever,

Fig. 5 is a bottom end view of the retriever, and

Fig. 6 is an enlarged side elevational view of the lower portion of the retriever.

I claim:

The ornamental design for a fishing lure retriever, as shown.

JOHN S. KNAUR.
